UNITED STATES PATENT OFFICE.

CHARLES W. BROWN, OF FRANKLIN, PENNSYLVANIA.

DESIGN FOR AN ICE-CREEPER.

SPECIFICATION forming part of Design No. 31,421, dated August 15, 1899.

Application filed July 8, 1899. Serial No. 723,250. Term of patent 7 years.

To all whom it may concern:

Be it known that I, CHARLES W. BROWN, a citizen of the United States of America, residing at Franklin, in the county of Venango and 5 State of Pennsylvania, have invented a certain new and useful Design for an Ice-Creeper, of which the following is a specification, reference being had therein to the accompanying drawings.

10 This invention relates to certain new designs in ice-creepers; and it consists in the novel form, as will be hereinafter more particularly described.

In the drawings, Figure 1 is a perspective 15 view of my design in ice-creepers. Fig. 2 is an inverted perspective view of the same.

Referring to the drawings by reference-numerals, 1 indicates the sides, which are curved

toward their free ends, the said sides terminating in an outwardly-projecting corner 2, 20 which is rounded and connected with a strip 3, said strip having an inward projection 4. A plate 5 extends from the lower portion of the strip 3 inwardly and carries a downwardly wedge-shaped portion 6. 25

Having thus fully described my invention, what I claim as new, and desire to secure by Letters Patent, is—

The design for an ice-creeper as herein shown and described. 30

In testimony whereof I affix my signature in the presence of two witnesses.

CHARLES W. BROWN.

Witnesses:

WM. B. GRIFFEN,

CYRUS S. MARK.
